(57) CLAIM

The ornamental design for a carrying case, as shown and described.

DESCRIPTION

This is related to co-pending U.S. Design patent application No. 29/225,102, entitled “Carrying Case for Communications Headset System” by applicant Soohyun Ham filed concurrently therewith.

FIG. 1 is a rear elevational view of a carrying case such as one for storing and transporting components of a communications headset and charger.

FIG. 2 is top plain view of the carrying case.

FIG. 3 is a left side elevational view of the carrying case.

FIG. 4 is a right side elevational view of the carrying case.

FIG. 5 is a front elevational view of the carrying case.

FIG. 6 is a lower rear left perspective view of the carrying case.

FIG. 7 is a bottom plain view of the carrying case; and,

FIG. 8 is an upper front right perspective view of the carrying case.
